MONITORING DEVICE

Wilmer C. Anderson, Greenwich, Conn., assignor
to Deering Milliken Research Trust, New York,
N. Y., a nonprofit trust of New York

Application January 31, 1948, Serial No. 5,580

14 Claims. (Cl. 28—64)

1

The present invention relates to the manufacture of yarn and more particularly to the inspection of yarn for detection and removal of oversized sections therein, and comprises a novel pneumatically operated yarn monitoring device which is simple and economical of construction, positive in action, and operates to cause breakage of the yarn when the diameter thereof exceeds a predetermined value over a predetermined length. The new device does not damage the yarn, can be threaded in one simple operation and is quick acting, permitting relatively rapid rate of yarn travel therethrough. The invention includes also a novel method of detecting and signalizing yarn diameter variations.

There are various known mechanical devices, called slab catchers, now in use in the textile industry, each of which operates to cut or break yarn whenever the diameter thereof exceeds a value for which the device is set. In general, these devices respond only to the diameter of the yarn and do not distinguish between slubs of different length. As very short slubs are ordinarily not objectionable, most known devices cut or break the yarn more often than is necessary. This results in an excess of knots in the yarn and in undue labor on the part of the operator who must remove the slab from one end of the yarn after severance by the device and tie the severed ends together. Moreover in the mechanical slab catchers now in use, the yarn in its travel is constantly engaged by the cutting or breaking members of the device and hence its surface becomes abraded or roughened during passage through the device.

There has thus been a decided need in the industry for a slab catcher that could distinguish between long and short slubs and that would not damage the surface of the yarn. As slab catchers are used at various stages of yarn manufacture, a great number are required in any one mill. Hence, it is of importance that the device be of simple and economical construction, that it operate without failure and that it can be easily and rapidly reset and rethreaded.

The monitor device of the present invention meets these and other desiderata. It discriminates between short and long slubs, allowing the former to pass and causing breakage of the yarn upon occurrence of the latter. It is of simple and durable construction and economical to operate. It has no sharp or rough edges for travel of yarn thereover and hence does not damage the yarn.

In the new slab catcher, air, or other compressible fluid, is delivered under pressure through a

2

restricted passage to a chamber from which it bleeds to the atmosphere through an orifice over which the yarn travels. When the yarn diameter exceeds a predetermined value over a predetermined length, the resulting increase in pressure in the chamber operates through a pressure responsive member to trigger a yarn holding element; the diameter of slab to be caught, and minimum length thereof, depending upon the adjustment of the triggering element, upon the supply pressure, upon the size of orifice and upon the rate of yarn travel.

For a better understanding of the invention, reference may be had to the accompanying drawings of which:

Fig. 1 is a top plan view of a pneumatic yarn monitor embodying the invention,

Fig. 2 is a front view of the device of Fig. 1,

Figs. 3 and 4 are side views of the device of Fig. 1 looking from the right and left respectively of Fig. 2,

Fig. 5 is a sectional view on the line 5—5 of Fig. 2, and

Fig. 6 is a sectional view of an alternative type of pressure head.

In the particular embodiment of the invention illustrated in Figs. 1 to 5, the various parts of the device are mounted on a base plate 2 which is secured, as by screw bolts 4 to a bracket 6 for convenient mounting on any suitable fixed part of a winding machine or other mechanism with which the device is to be used. Two L-shaped support members 8 and 10 are positioned respectively above and below the base 2 with one leg of each secured thereto by bolts 12. The other leg 8' of member 8 supports the pressure responsive element and associated parts of the device now to be described and the other leg 10' of member 10 supports a conventional yarn guide and tensioner 14.

The pressure responsive element comprises a circular diaphragm 16 (see Fig. 5) which is clamped, adjacent its periphery, between a disk 18 and an annular flange 20 of a cylindrical member 22 as by means of screws 24. Certain of the screws 24 pass through the leg 8' of support 8 and serve to secure the cylinder 22 to the support; the leg 8' being cut away, as shown, for reception of the body of the cylinder. The disk 18 has a central aperture therein which is screw threaded for reception of a turned down and externally threaded portion 26 of the yarn gauging head 28. Head 28 comprises a generally frusto-conical member having an external annular groove 28' for guiding yarn in its travel

through the device. Portion 26 and the central part of head 28 are reamed out to provide a pressure chamber 30 communicating with one side of diaphragm 16. An air inlet tube 32 extends into a passage 32' in element 28 leading from the face of the element to chamber 30, the tube 32 being press fit and welded or soldered to the wall of the passage or otherwise tightly secured in place so as to prevent leakage of air. The passage 32' and tube 32 are of relatively small cross section so as to offer substantial impedance to the flow of air therethrough. The head 28 is provided with a pair of closely adjacent radial passages 34 of relatively small bore which connect chamber 30 with the annular groove 28' and terminate in orifices 34'. Only one passage 34 appears in the sectional view Fig. 5.

Cylinder 22, is externally threaded for a portion of its length and is provided with a pair of diametrically disposed longitudinal slots 36. An adjusting collar 38 is screw threadedly mounted on the threaded portion of cylinder 22 and a centrally apertured cap 40 is threaded over the end of the cylinder remote from the pressure sensitive diaphragm 16. A rod 42 is axially disposed within the cylinder 22 with one end extending through the aperture in cap 40 and its other end secured to a disk 44 which fits within the cylinder 22 and engages the diaphragm 16. The disk 44 is urged against the diaphragm 16 by a coiled spring 46, one end of which engages the disk 44 and the other end of which engages an annular member 48 within the cylinder. Member 48 has two radial pins 50 secured thereto which extend through the longitudinal slots 36 and engage the collar 38. A lever 52 is pivotally mounted in a yoke 54 rigidly secured to the cap 40. Lever 52 has an elongated slot 56 therein for reception of the end of rod 42 and has a smaller elongated slot 58 therein intersecting the slot 56 at right angles. A pivot pin 60, extending through the slot 58 and through the rod 42, couples the rod and lever together.

The mechanism triggered in response to a predetermined angular movement of lever 52 about its pivot resulting from a predetermined increase in pressure in chamber 30 will now be described.

A post 62, mounted on the base 2, pivotally supports a bell crank lever 64 comprising a long arm 64a and a short bifurcated arm 64b. A rod 66, having a relatively heavy end or head 68, is slidably mounted in a pair of spaced supports 70 which extend up from the base 2 and are rigidly secured thereto by screws 72. The rod 66 has a collar 74 adjustably secured thereto which is engaged on one side by the furcations of arm 64b and on the other side by one end of a compression spring 76; the other end of the spring engaging the rear support 70. Spring 76 thus tends to move rod 66 forwardly into the position illustrated in dotted lines in Fig. 1. Lever 52 is provided with a collar 78 which, in the normal position of lever 52, engages a finger 80 on the end of arm 64a and prevents clockwise movement (as viewed in Fig. 1) of the bellcrank lever 64 and hence, through arm 64b, holds rod 66 in the retracted position indicated in solid lines in Fig. 1. A plate 82 secured, as by screws 83, to the base 2 serves as a stop for limiting the forward movement of the head 68 of rod 66, the upper part of the plate being turned outwardly, as indicated in the drawing, for easy insertion of yarn between the hammer 68 and the stop during the threading operation. A plate or wall section 84 secured to the base 2 at right angles to the plate 82 has

an elongated, partly open sided, slot 84' cut therein which serves as a guide for yarn in its exit from the device.

The tension device 14 comprises a pair of bell washers 86 which are rotatably mounted on a rod 88 extending through the leg 10'. Light pressure between the washers is provided by a compression spring 90 positioned about the rod 88 between the rear surface of the leg 10' and a collar 92 fixed to the rod. A cap 94 on the forward end of rod 88 completes the assembly of the tension device.

Yarn, indicated by the reference numeral 96, travels through the above described slub catcher in the direction indicated by the arrows in Fig. 2. The yarn is supplied from any suitable source and drawn through the device by any suitable take up means; neither the supply nor take up mechanism, being shown in the drawings, as such mechanisms are normal components of mill equipment. Yarn 96 travels between the bell washers 86, makes a quarter turn around the head 28, riding in the groove 28' over the orifices 34', then passes between the hammer 68 and plate 82 and out through the slot 84' in guide 84. As the path of the yarn includes no closed guide rings or enclosed passages, threading of the device is simple and rapid, requiring only a looping of a stretch of the yarn around the tension device and head 28 and the insertion of the stretch into the open sided slot 84'.

During operation of the device, air under pressure is delivered through the supply pipe 32 to the chamber 30, from whence it bleeds to the atmosphere through the passages 34. The yarn, travelling in the groove 28', passes over the orifices 34' and offers an impedance to the airflow which varies with the yarn diameter. The parts are so adjusted relative to the rate of travel of the yarn, that when the diameter of the yarn over a predetermined length exceeds a predetermined value, say 200 percent of average diameter, the pressure in chamber 30 increases to a value sufficient to trip the hammer 68 by release of the holding finger 80; the pressure in chamber 30 acting through diaphragm 16 and rod 42 to swing lever 52 outwardly and thereby move collar 78 out of engagement with finger 80. When finger 80 is released, spring 76 forces hammer 68 into the dotted line position of Fig. 1 in which position the yarn is firmly gripped between the hammer and plate 82. The continuing tension of the take up mechanism causes the yarn to break when so held by the device. Upon breakage of yarn the operator removes the oversize section of yarn, resets the device by moving arm 64a into position where finger 80 is engaged by the collar 78, ties the ends of the yarn together and rethreads the device.

The above described pneumatic slub catcher may be readily adjusted for detection and elimination of slubs of different minimum diameter and length by adjustment of collar 38 to vary the compression of spring 46. For a given rate of travel of the yarn, increase in compression of the spring increases the minimum diameter of a given length of yarn or the minimum length of a given diameter of yarn necessary for tripping the device.

Two closely spaced outlet passages, rather than a single outlet passage have been shown in the drawings, as such construction reduces the tendency toward turbulence and hence is preferred. In designing the head 28 the passage 32' and tubing 32 are made of such size that the impedance offered thereby to the air flow will be

substantially equal to that offered by the yarn when of average diameter so that the normal pressure in chamber 30 is substantially half that of the supply pressure. A device constructed in accordance with the above described embodiment of the invention and having substantially the proportions indicated in the drawings has been used satisfactorily to catch slubs in yarn having a cotton count of 12's and travelling at 25 feet per second. The size of the orifices 34' of such device was .001 square inch. With a supply pressure of ten pounds per square inch, the device operated to catch slubs in the yarn of over one-half inch in length and of a diameter of at least twice the average diameter of the yarn.

The optimum total cross section of the outlet passages 34' depends upon the average diameter of the yarn to be handled. With the construction illustrated in Figs. 1 to 5, the pressure head 28 may be readily removed for replacement by a head having outlet passages of different cross section when yarn of different average diameter is to be handled. A construction of pressure head which can be adjusted for use with yarns of different average diameter is shown in Fig. 6.

In Fig. 6 the pressure head 28a is made up of three sections 98, 100 and 102, which are held together by a bolt 104 passing axially through portions 100 and 102 and screw threaded into the portion 98; a lead washer 106 being provided between the head 28a of the bolt and the outer surface of portion 102 to insure a substantially airtight fit. An annular flange 18a of portion 98 is secured, like disk 18 of the construction of Figs. 1 to 5, to the parts 29 and 30' of the device by the screws 24; the diaphragm 16 being gripped between the parts 18a and 29. Portion 98 has the pressure chamber 30a formed therein and is provided with a passage 110 which is offset radially from the axis of the head and aligned with a similarly radially offset inlet passage 112 in portion 102 of the head 28a. Portion 100 is provided with a plurality of radial outlet passages of different cross section of which two, indicated at 114 and 116, appear in the cross-sectional view Fig. 6. The portion 100 is provided with a number of longitudinal passages 118 equal to the number of outlet passages and adapted to be individually brought into alignment with the passages 110 and 112 in portions 98 and 102 respectively by rotation of the portion 100 about the common axis of the head 28a; each longitudinal passage 118 intercepting one radial passage. To permit rotation of the central portion 100 while preventing rotation of portion 102, a sheath 120 is provided about the bolt 104 and this sheath is of rectangular cross section at each end while of circular cross section for the stretch extending through the portion 100; the sheath fitting into correspondingly shaped axial holes in the three portions of the head.

Any suitable means may be provided for rotating the portion 100 to bring a different outlet passage 118 into alignment with passages 110 and 112 when yarn of different average diameter is to be handled. In the particular construction illustrated in Fig. 6, the portion 100 is provided on its outer surface with radial cavities 122 for reception of suitable pins or keys by means of which, when bolt 104 is loosened, the portion 100 may be adjusted to any desired position. With this arrangement the smooth contour of the head 28a, making for easy threading of the device, is not disturbed.

Preferably, as shown at 124, a suitable detent

is provided for insuring proper alignment of the passages after angular movement of the portion 100. Any suitable means, such as the ring seals indicated diagrammatically at 126 may be provided for preventing undue leakage of air from the device.

From the above description it will be apparent that when portion 100 is in the angular position shown in Fig. 6 and air under pressure is delivered to the inlet passage 112, outlet passage 114 is connected to the inlet passage and to chamber 30a and hence the pressure acting on the diaphragm 16 will be responsive to the diameter of yarn 96 passing over the terminal orifice of passage 114. In this position of the portion 100, the longitudinal passage 118 communicating with outlet passage 114 is in alignment with passages 110 and 112 but all of the other longitudinal passages 118 are blocked at their ends by the surfaces of portions 98 and 102. When a yarn of a different average diameter is to be handled, for example, one for which the outlet orifice of passage 116 is suitable, it is only necessary to unscrew bolt 104 sufficiently to permit relative rotation of portion 100, insert a pin or key in a cavity 122 and rotate portion 100 through 180° until the detent 124 slips into the cooperating indentation 124' in the surface of portion 100. In this position of the parts, a passage 118 will be in communication with the air inlet passage and with the chamber 30a and the terminal orifice of passage 116 will be in the path of travel of the yarn.

The radial passages of the portion 100 of head 28a could be, and preferably would be, in pairs, like the passages 34 of Figs. 1 to 5 as such construction reduces any tendency to turbulence of the emitted air.

The invention has now been described with reference to one specific embodiment thereof and with reference to a modification of one part. Obviously, various changes could be made in the illustrated constructions without departing from the spirit of the invention as defined in the appended claims. It will be apparent that the pneumatic slab catcher of the invention comprises an efficient device wherein increase in fluid pressure occasioned by a slab in the yarn is utilized to trip a mechanism which catches or holds the yarn so that the slab may be removed, the yarn itself forming part of a variable orifice through which the fluid escapes under pressure to the atmosphere. As the yarn in its travel through the device engages only smooth rounded surfaces, it is not subjected to wear or damage as in mechanical slab catchers heretofore in use. Moreover, because tripping of the yarn holding mechanism occurs only when the diameter of a predetermined length of yarn exceeds that desired, short unobjectionable slubs or neps will travel through the device without actuation of the hammer, with corresponding conservation of time and labor of the attendant.

The term "yarn" in the foregoing description and in the appended claims is intended to include any textile filamentary material, whether of one or of a plurality of filaments, whether formed of staple fibers or of continuous filaments and whether twisted or untwisted.

The following is claimed:

1. The method of detecting slubs in yarn which comprises passing yarn over an orifice, detecting changes in impedance to fluid flow through the orifice occasioned by changes in the diameter of the yarn and arresting the travel of the yarn

when the detected impedance exceeds a predetermined value.

2. The method of detecting slubs in yarn which comprises supplying air under pressure through a restricted passage to a chamber from which it may escape through an orifice to the atmosphere, passing yarn over the orifice to vary the pressure in the chamber in accordance with variations in the diameter of the yarn, and arresting the travel of the yarn when the pressure in the chamber exceeds a predetermined value.

3. A device for detecting slubs in yarn comprising in combination an element having a chamber therein and provided with restricted inlet and outlet passages for compressible fluid communicating with said chamber, said outlet passage terminating on the external surface of said element for passage of yarn thereover, a pressure responsive member having a face exposed to the pressure in said chamber, a mechanism adapted when actuated to arrest the travel of yarn and means controlled by said pressure responsive member for actuating said mechanism when the pressure in said chamber exceeds a predetermined value corresponding to a predetermined increase in the diameter of yarn passing over the surface of said element.

4. The device according to claim 3 wherein the outlet passage terminates in a groove in the external surface of said element, the groove serving to guide the yarn in its passage over the surface of the element.

5. The device according to claim 3 wherein said element includes at least one other outlet passage and means whereby the connection between said first mentioned outlet passage and said chamber may be broken and said other outlet passage connected to said chamber, said other outlet passage when connected with said chamber terminating on the external surface of the element for passage of yarn thereover.

6. The device according to claim 3 wherein said mechanism includes a hammer biased into yarn holding position and latch means normally restraining movement of said hammer, said means controlled by said pressure responsive element operating to actuate said mechanism by tripping said latch means.

7. A pneumatic slab catcher comprising in combination an element cut away at one end to form a reentrant chamber, a diaphragm secured to said element and forming a moveable wall of the chamber, said element being provided with a restricted inlet passage for air under pressure communicating with said chamber and with an outlet passage terminating in an orifice on the surface of the element for travel of yarn thereover, a plunger biased into engagement with said diaphragm, a latch controlled by said plunger for release upon a predetermined movement of the plunger, and yarn holding mechanism actuated upon release of said latch.

8. The slab catcher according to claim 7 wherein said element is provided with a second outlet passage terminating in an orifice for travel of yarn thereover, said passages being closely spaced and terminating in a smooth peripheral arcuate groove in the surface of the element serving as a guide for yarn in transit through the device.

9. The slab catcher according to claim 7 wherein said element is provided with additional outlet passages each adapted to be brought into exclusive communication with said chamber, each of said outlet passages terminating in an orifice on the surface of said element, each of

said orifices, when the associated passage is brought into communication with said chamber, being in a position for passage of yarn thereover.

- 5 10. A pneumatic slab catcher comprising a base, a bracket secured thereto, a pair of annular members mounted on said bracket, a plate secured to said base and having a surface for passage of yarn thereover, a hammer slidably mounted on said base adjacent said surface, means biasing said hammer toward said surface, releasable means normally holding said hammer in retracted position, a diaphragm secured at its periphery between said annular members, an element secured to one of said members and having a chamber formed therein communicating with one wall of said diaphragm, said element being provided with a restricted air inlet passage communicating with said chamber and with an air outlet passage leading from said chamber and terminating in an orifice on the surface of the element for passage of yarn thereover, a frame member secured to the other of said annular members, a plunger slidably mounted in said frame member with one end engaging said diaphragm, a lever pivotally mounted at one end on said frame member and linked to said plunger and means carried by the free end of said lever for releasing said restraining means upon predetermined angular movement of said lever.

11. The slab catcher according to claim 10 including a yarn tension device mounted on said base in the path of travel of yarn to the surface of said element and a fixed yarn guide mounted on said base in the path of travel of yarn from the surface of said plate.

12. The slab catcher according to claim 10 wherein said element is removably secured to the annular member.

13. The slab catcher according to claim 10 wherein said element is provided with a second outlet passage leading from said chamber and terminating in an orifice adjacent the first mentioned orifice and in the path of travel of yarn.

14. A yarn monitor device comprising in combination, an element having a smoothly rounded surface for passage of yarn thereover, a chamber within said element for fluid under pressure, said element being provided with a restricted inlet passage leading to said chamber and with an outlet passage leading from said chamber and terminating at said surface, mechanism adapted, when actuated, to signify the occurrence of a slab in yarn travelling over said surface and means sensitive to the pressure in said chamber for actuating said mechanism when the pressure in said chamber exceeds a predetermined value, whereby, when air under pressure is delivered to said chamber and bleeds to the atmosphere around yarn travelling at a constant rate over the end of the outlet passage on said surface, said mechanism is actuated when a slab of a length greater than a predetermined length and of a diameter greater than a predetermined value travels over the end of the outlet passage.
